UNITED STATES PATENT OFFICE.

HENRY J. WEIERSHAUSER, OF STOCKTON, CALIFORNIA.

METHOD OF FILLING ENGINE GAS-TANKS.

1,393,861.

Specification of Letters Patent. Patented Oct. 18, 1921.

Application filed April 5, 1920. Serial No. 371,472.

To all whom it may concern:

Be it known that I, HENRY J. WEIERSHAUSER, a citizen of the United States, residing at Stockton, in the county of San Joaquin, State of California, have invented certain new and useful Improvements in Methods of Filling Engine Gas-Tanks; and I do declare the following to be a full, clear, and exact description of the same, reference 10 being had to the accompanying drawings, and to the characters of reference marked thereon, which form a part of this application.

This invention relates to improvements 15 in methods of filling engine gas tanks, especially the gas tanks on tractors and the like.

When these machines are in the field during the preparation of large areas of ground 20 for planting, etc., they are very often away from headquarters for extensive periods. It is therefore customary to carry auxiliary gas drums or reservoirs, from which the engine gas tank may be refilled when necessary. This is done at present by means of a 25 hand suction pump, which is a slow and arduous procedure.

The principal object of my invention therefore is to devise a method of refilling 30 the engine tank by means of the vacuum obtained with the operation of the engine, with the aid of a simple appliance on the gas tank and suitable connections to the engine.

35 A further object of the invention is to produce a simple and inexpensive device, and yet one which will be exceedingly effective for the purposes for which it is designed.

40 These objects I accomplish by means of such structure and relative arrangement of parts as will fully appear by a perusal of the following specification and claims.

In the drawings similar characters of reference indicate corresponding parts in the several views.

Figure 1 is a side outline of a form of tractor, showing my improved tank filling device installed thereon.

50 Fig. 2 is an enlarged sectional view of a control valve.

Referring now more particularly to the characters of reference on the drawings, the numeral 1 denotes in general a tractor having a gas engine 2 and a gas tank 3. The engine of course has a carbureter 4 con-

nected with the combustion chambers of the engine by the usual manifold 5.

In carrying out my improved method, I employ a small auxiliary gas tank 6 connected with the carbureter intake by a pipe 7 and with the main tank 3 by a pipe 8, the latter having a shut off cock 9 interposed therein.

A float valve member 10 is fixed in the top of the tank 3, comprising a body 11 having communication with the tank 3, in which is slidably mounted a needle valve 12 having a float 13 on its lower end.

This valve when raised is adapted to seat 70 in the lower end of a connection 14, to which is secured one end of a pipe 15, the other end of said pipe being connected to the manifold 5.

A shut off cock 16 is interposed in the pipe 15, and also a check valve 17 near the manifold, and operating to prevent a flow from said manifold into the pipe.

To the body 11 below the needle valve 12 is connected one end of a flexible hose 18, 80 the other end being adapted to be placed into a gas drum 19 positioned on the ground or elsewhere.

The operation of the device is as follows:

The valve 9 between the main and auxiliary gas tanks is first closed, and the engine started, drawing its fuel supply from the auxiliary tank.

The running of the engine creates a vacuum in the manifold 5, which of course 90 draws air through the pipe 15 when the cock 16 is opened.

The air in the tank 3, the latter being air tight, is of course soon exhausted, and liquid from the tank 19 is forced through the hose 95 18 which is immersed therein, by reason of the atmospheric pressure thereon. The opening of the body 11 into the tank 3 being very much greater than the pipe 16, the liquid will flow downwardly into said tank, 100 rapidly filling the same.

When the tank is full, the float 13 will rise and shut off the pipe connection 14, preventing any more liquid from being drawn into the tank. The cock 16 may then be closed, the 105 cock 9 opened, and the hose 18 removed from the drum and uncoupled or hung at any convenient point, the hose or its opening forming the necessary air vent for the gas tank.

A valve 7^a is placed in the pipe 7 between the tank 6 and the carbureter, which is

closed when the tractor is drawing its supply from the main tank 19 through the pipe 19^a, so that the tank 6 will fill from the main tank, and will then be available when the 5 main tank is empty.

From the foregoing description it will be readily seen that I have produced such a device as substantially fulfills the object of the invention as set forth herein.

10 While this specification sets forth in detail the present and preferred construction of the device still in practice such deviations from such detail may be resorted to as do not form a departure from the spirit of the 15 invention, as defined by the appended claims.

Having thus described my invention what I claim as new and useful and desire to secure by Letters Patent is:—

1. A hollow body member adapted to be 20 secured on the upper side of an engine gas-tank over an orifice therein, a pipe leading from the top of the body to the intake manifold of the engine, a vertically movable float-valve mounted in the body and adapted to close said pipe when the tank is full, and a relatively large pipe leading from one 25 side of the body below the first named pipe and adapted to be immersed in a source of fuel supply.
- 30 2. A hollow body member adapted to be secured on the upper side of an engine gas-tank over an orifice therein a pipe leading from one side of the body and adapted to be immersed in a source of liquid fuel supply, a 35 relatively small pipe connected to the top of the body member and to the intake manifold of the engine, a stem slidably mounted in the body for limited vertical movement and adapted to form a closure for said last

named pipe, and a float on the lower end of 40 the stem and projecting into the tank, the diameter of the float being less than that of the tank-orifice, whereby the entire structure may be removed from the tank as a unit.

3. A hollow body member adapted to be 45 secured on the upper side of an engine gas-tank over an orifice therein, a pipe leading from the top of the body to the intake manifold of the engine, a valve mounted in the body and adapted to close said pipe when 50 the main tank is full, a pipe leading from one side of the body and adapted to be immersed in a source of supply, and a float for operating said valve depending below said body member and into the tank. 55

4. In combination with a gas engine, a permanent fuel supply tank therefor having communication with the carbureter of the engine, and an exterior source of supply; means for filling the permanent tank from the exterior source by the suction of the engine, and an auxiliary fuel tank connected to the permanent tank to supply the engine with fuel to operate the same while the permanent tank is being filled but shut off 60 from communication therewith at such time.

5. In combination with a gas engine, a permanent fuel supply tank therefor having communication with the carbureter of the engine, and an exterior source of supply; means for filling the permanent tank from the exterior source by the suction of the engine, an auxiliary fuel tank, a pipe connecting both tanks, another pipe connecting the auxiliary tank with the carbureter, and shut- 75 off cocks interposed in both pipes.

In testimony whereof I affix my signature.
HENRY J. WEIERSHAUSER.
